US0D1087388S

(12) **United States Design Patent** (10) **Patent No.:** **US D1,087,388 S**
Cota et al. (45) **Date of Patent:** **** Aug. 5, 2025**

(54) **CARTRIDGE CARRIER**

- (71) Applicant: **Becton, Dickinson and Company**, Franklin Lakes, NJ (US)
- (72) Inventors: **Raymond Brasil Cota**, San Jose, CA (US); **Jamie Ryan Moskwa**, San Jose, CA (US); **Germin Hanna Zaki**, Sunnyvale, CA (US); **Jrhung Taylor Tsai**, Alameda, CA (US); **Yasaman Daghighi**, Oakland, CA (US); **Timothy Zheng Zhu**, San Jose, CA (US)
- (73) Assignee: **Becton, Dickinson and Company**, Franklin Lakes, NJ (US)
- (**) Term: **15 Years**
- (21) Appl. No.: **29/988,330**
- (22) Filed: **Jan. 31, 2025**

Related U.S. Application Data

- (62) Division of application No. 29/883,852, filed on Feb. 3, 2023, now Pat. No. Des. 1,066,734.
- (51) **LOC (15) Cl.** **24-02**

Primary Examiner — Justin C Dodson*Assistant Examiner* — Eric Eldone Tormanen(74) *Attorney, Agent, or Firm* — Edward J. Baba; Bret E. Field; BOZICEVIC, FIELD & FRANCIS LLP(57) **CLAIM**

The ornamental design for a cartridge carrier as shown and described.

DESCRIPTION

FIG. 1 is a front side view of a cartridge carrier;
FIG. 2 is a rear side view of the cartridge carrier;
FIG. 3 is a top view of the cartridge carrier;
FIG. 4 is a bottom view of the cartridge carrier;
FIG. 5 is a top perspective view of the cartridge carrier;
FIG. 6 is a bottom perspective view of the cartridge carrier;
FIG. 7 is a first side view of the cartridge carrier; and,
FIG. 8 is a second side view of the cartridge carrier.
